(57) **CLAIM**

The ornamental design for a display screen or portion thereof with a graphical user interface for managing an assessment as shown and described.

DESCRIPTION

The FIGURE is a display screen or portion thereof with a graphical user interface for managing an assessment showing the new design.

The outer perimeter shown as long-dash broken line in the drawing illustrates a display screen or portion thereof and forms no part of the claimed design. The remaining broken lines in the drawing illustrate portions of the graphical user interface that form no part of the claimed design.
